(57) **CLAIM**

The ornamental design for camera stand with flash as shown and described.

DESCRIPTION

1.1 is a top view of a camera stand with flash;

1.2 is a right side view thereof;

1.3 is a left side view thereof;

1.4 is a front view thereof;

1.5 is a top, front, right perspective view thereof;

1.6 is a rear view thereof; and

1.7 is bottom view thereof.

(Continued)

The broken lines shown in the drawings depict portions of the camera stand with flash and form no part of the claimed design.

1 Claim, 7 Drawing Sheets
